UNITED STATES PATENT OFFICE.

HUGO REICHEL, OF CHICAGO, ILLINOIS.

VALVE-SEPARATOR MACHINE.

Application filed March 28, 1927. Serial No. 178,946.

This invention relates to improvements in valve separator machines and more particularly to novel methods and improved devices for removing valves from rubber 5 tires and the like and for separating the iron portions of the valves from the brass portions.

An object of the invention is to provide a valve separator machine which is especially adapted for removing valves from the inner tubes of automobile tires and the like.

Another object of the invention is to provide a valve separator machine which is adapted to remove the valve stem from the 15 tube and to separate the iron portion of the valve from the brass portion by a single operation of the machine.

A further object of the invention is the provision of a machine of the class described 20 which is simple in construction, easily operated and adapted for economical manufacture.

A still further object is the general improvement of valve separator machines of 25 the class described.

With the above and other objects in view, the invention consists in the novel methods and in the typical details of construction and in the arrangement and combination of 30 parts hereinafter more fully described and particularly pointed out in the appended claims.

In describing the invention in detail, reference will be had to the accompanying 35 drawings, wherein like characters of reference denote corresponding parts in the several views, and in which

Figs. 1 and 2 are respectively front and side elevational views of the machine;

Fig. 3 is a plan view of the machine;

Fig. 4 is a view along the line 4—4 of Fig. 1;

Fig. 5 is an enlarged sectional view of a portion of the machine showing an inner tube in position for removal of the valve therefrom; and

Fig. 6 is a view along the line 6—6 of Fig. 3.

Referring to Figs. 1 and 2 of the drawings, the machine comprises a supporting frame 10 having a crank shaft 11 mounted thereon. The shaft 11 is carried by two bearings 13 between which is located a sliding box 14, shown in sectional detail in Fig. 6. A T head 15 mounted on the sliding

box 14 and extends downwardly inside a way 16, the front of said way being covered by a plate 17.

The supporting frame carries the parts of a die couple which are movable relatively to each other. The die couple comprises a punch member which is made up of a punch block 18 and a punch 20. The punch block 18 is mounted on the lower end of the T head 15 and projects through a member 19 which serves as a guide for the punch 20. The die couple also includes a die block 21, carrying a die 22, which is normally positioned immediately beneath the punch member. A knife 23, carried by the T head 15, is mounted just back of the punch block 18. The knife 23, cooperates with the punch member and extends downwardly substantially the same distance as does the punch 20, the purpose and function of the knife being hereinafter more particularly explained.

A driving wheel 12 is mounted upon one end of the shaft 11 and is freely rotatable thereon. The wheel 12 is operatively connected in any convenient manner with a source of power, not shown, and rotates substantially continuously while the machine is in use.

The die block 21 with a tube 24, operatively positioned on the block, are shown in detail to an enlarged scale in Fig. 5, with a valve which is to be removed from the tube, extending down through the die 22. The valve, which is to be removed from the tube 24 and separated into its component parts by one operation, is made up of the usual parts. These parts include a threaded valve housing 27 and an inner washer 26, both manufactured of brass, and an outer iron washer or retaining member 25, all of which are tightly and firmly connected so as to require great pressure to separate them.

In its operative position the die 22 is positioned immediately underneath the punch 20 and in close proximity thereto in order that vertical movement of the punch be kept at a minimum. The close proximity of the die 22 and punch 20 makes it desirable that the die be removed from underneath the punch for the purpose of locating the tube 24 on the die. For this purpose the die 22 is mounted on the upper end of a vertically extending auxiliary frame 28 having a pedal 29 at-

tached to the lower end thereof. The frame 28 is pivotally mounted on a pin 30 which permits the die 22 to be moved laterally towards the operator by exerting pressure on the pedal 29. A tensile spring 31 is provided to pull the frame 28 back to its normal position, when the pedal 29 is released, thereby carrying with it the die 22 and the tube 24 which has been positioned 10 thereon.

The return movement of the frame 28 to its original upright position sets in motion a device which connects the T head 15 with the driving wheel 12 and thereby actuates 15 the punch 20, causing it to move downwardly from its normal position as is best shown in Fig. 5, to a position where it contacts with and forces the valve out of the tube 24 and into its component parts as 20 hereinafter more particularly described. The device which starts the punch 20 in motion includes a clutch trip member 32 which is fastened to the frame 28 by bolts 34. The member 32 extends rearwardly where it 25 contacts with and actuates a punch rod 35 when the frame 28 is returned to its vertical position.

The rear end of the trip member 32 is provided with a lug 36 which has its outer 30 edge or face beveled. A finger 39, having its forward face beveled, is pivotally mounted on the lower end of the punch rod 35 by means of a bolt 40. The finger 39 is free to rotate from its vertical position towards the operator and back to its vertical 35 position, as shown in Fig. 2, but is prevented from moving past its vertical position in the opposite direction by the provision of suitable means such as a lug (not shown). The lug is not shown as it is a common and well 40 known device for limiting rotation and is not a part of the invention. A guide member 37 is bolted to the side of the frame 10. The rod 35 passes through the member 37, 45 the latter serving to prevent all motion of the rod 35 other than in a longitudinal direction. A tensile spring 38 connects the upper end of the rod 35 with the guide member 37 and yieldingly holds the rod 35 50 in the position shown in Fig. 2.

When the operator presses down on the pedal 29 and thereby moves the frame 28 outwardly, the trip member 32 is carried by the vertical frame 28 to the dotted line position of Fig. 2. In moving the lug 36 forwardly, the finger 39 gives way before the lug 36 and drops down again to its vertical position after the lug has passed. Upon releasing the pedal 29, the frame 28 returns to 60 its normal vertical position carrying with it the trip member 32 and thereby brings the beveled face of the lug 36 into contact with the beveled edge of the finger 39. Since the finger 39 can not swing or yield beyond its 65 vertical position, the pressure of the lug 36

forces the rod 35, on which the finger 39 is mounted, upwardly against the tension of the spring 38, sufficiently to let the lug pass to its full line position as shown in Fig. 2. When the lug 36 has reached its normal 70 position, the spring 38 pulls the rod 35 and finger 39 back to the position shown.

The upward movement of the punch rod 35, caused by the inward movement of the frame 28, and the downward movement of 75 the rod 35 which is caused by the pull of the spring 38, produces a cycle of operations resulting in one complete actuation of the punch 20, this result being attained by reason of the connection of the rod 35 with a device adapted for connecting the driving wheel 12 with the crank shaft 11. For this purpose the crank shaft 11 has a longitudinally extending key 42 which is normally completely recessed therein with one end of the key in close proximity to the driving wheel 12. The key 42, when in its normally recessed position, permits the wheel 12 to rotate about the shaft, being held in said recessed position in the shaft 11 by a lug 44. 80 The lug 44 is fastened on one end of a rod 45 which is rotatably mounted in a main guide lug 46, the lug 46 being shown as integrally formed with the frame 10. The punch rod 35 is connected to the other end of the rod 45 by means of an eccentric collar 47, as shown in Figs. 2, 3 and 6, whereby vertical motion of the rod 35 produces corresponding oscillation of the rod 45 and the lug 44. 85

The punch rod 35 is shown in Fig. 4, in its extreme uppermost position. This position results from the thrust of the lug 36 against the finger 39, as previously described, upon the return of the clutch trip member 32 to its normal position following the release of the pedal 29. In this position of the rods 35 and 45, the lug 44 has been rotated away from the shaft 11 with which the lug is in contact when the rod 35 is in its lowermost position. A compression spring 48, which is positioned back of the key 42, exerts a constant outward pressure on the key so that when the lug 44 has been turned to clear the shaft 11, the spring forces the 105 key from its recessed position to the position shown in Fig. 4. The rod 45 is held in adjustable longitudinal position by collars 49 and 50, positioned one on either side of the main guide lug 46. 110

A pair of pins 51 are mounted in the hub of the wheel 12 and project sufficiently that the nearest will engage the key 42 when the key is in the position shown in Fig. 4. The pins 51 clear the key 42 when the key is in its normally recessed position in the shaft 11. The contacting faces of the key 42 and of the lug 44 are beveled and, when the lug 44 is returned to its normal position of close contact with the shaft 11, the key 42 is forced 115 120 125 130

back, against the pressure of the spring 48, to its innermost recessed position in the shaft 11. The engagement of the pins 51 with the key 42 will thus cause one complete rotation of the shaft 11 upon release of the key 42 and, if, during this rotation of the shaft, the lug 44 is returned to its position of close contact with the shaft, the key 42 will be forced back into its normal recessed position at the completion of the first rotation and the shaft 11 will come to a stop with the key 42 underlying the lug 44. To insure the stoppage of the shaft 11 with the key 42 in its recessed position, a brake 52 is provided which retarded the shaft and brings it to an abrupt stop as soon as the key 42 is released from contact with the pin 51. The brake 52 is adjusted by means of a brake knob 53.

A complete cycle of operations resulting in the removal of the valve from the tube and the separation of the brass portions of the tube from the iron portion thus results from moving the die 22 out from under the punch 20 by the operator exerting pressure upon the pedal 29, following this with positioning the tube as shown and then releasing the pedal. The spring 31 pulls the frame 28 and the die 22 back to their normal position and cause the lug 36 to force the finger 39 and the punch rod 35 upward sufficiently to permit the lug to pass under the finger. The rod 35 remains in this upper position for only an instant but during this instant the lug 44 has been turned to the position shown in Fig. 4, and the key 42 has moved to its unseated position therein shown. The resulting engagement of the pin 51 with the key 42 causes the shaft 11 to rotate with the wheel 12. The lug 44 is immediately returned to its position of close contact with the shaft 11 by reason of the downward movement of the rod 35, which follows close after the passing of the lug 36 under the finger 39, this movement being expedited by the pull of the tensile spring 38 upon the rod 35.

The substantially instantaneous return of the lug 44 to its position of contact with the shaft forces the key 42 back into its recessed position upon completion of one revolution of the shaft 11 with the wheel 12. The disengagement of the key 42 from the pin 51 prevents further rotation of the shaft 11. The retarding effect of the brake 52 brings the shaft 11 to an immediate stop with the lug 44 in operative contact with the key 42 whereby the key is held in its recessed position until another cycle of operations is started by the release of the pedal 29.

The sliding box 14 and the T head 15 are so mounted upon the shaft 11 that, during the first half of the revolution of the shaft, the T head 15 is forced downwardly carrying with it the punch block 18 and the punch 20. The punch 20 is thereby brought

into contact with the tube 24 and forces the punch through the tube into contact with the valve stem 27 at its juncture with the brass washer 26. The punch 20 is carried by the operation down to a point where the valve stem 27 is forced free from the brass washer 26 and free from the retaining member or iron washer 25, after which it drops through the die 22 into a trough 54, suitably positioned to receive and carry off the same. The knife 23 is simultaneously carried down and pierces the tube adjacent to the valve connection. During the second half of the rotation of the shaft 11, the T head 15 is carried to its extreme upward position whereby the punch 20 and the knife 23 are removed from contact with the tube. The brass washer 26 is then removed from the tube through the slit, resulting from the knife 23 piercing the tube, and are dropped into the trough 54 with the brass member 27 or otherwise disposed of as desired. The tube 24 is then removed from its position on the die 22 and the iron washer 25 disposed of in any suitable manner thereby completing the operation.

Thus it will be seen that I have provided a device which is adapted to remove the valve from a tube or the like and to separate the brass portions of the valve from the iron portion at one operation.

Having thus described my invention and illustrated its use, what I claim as new and desire to secure by Letters Patent is:

1. In a device of the character described, in combination, a die having a vertically disposed aperture therein, and a punch member adapted to be introduced under pressure against an object mounted upon said die and into said aperture, and a knife adjacent to and movable with said punch member.

2. In a device of the character described, a supporting frame, a die couple, the parts of said die couple being relatively movable on and supported by said frame, a substantially continuously operating driving member disconnectably connected to one of the parts of said die couple, and means operated by displacement of one of the parts of the die couple for transmitting a complete movement to the other part of the die couple by momentary connection of the latter to said driving member.

3. In a device of the character described, in combination, a die having a vertically disposed aperture therein, and a punch member adapted to be introduced under pressure against an object mounted upon said die and into said aperture, a die block disposed adjacent to said die, a knife cooperating with said die block, and means for moving said die and die block out of the path of movement of said punch member and knife for receiving such object.

4. In a device of the character described, in combination, a supporting structure, a die carried thereby having a vertically disposed aperture therein, and a punch member carried by said supporting structure adapted to be introduced under pressure against an object mounted upon said die and into said aperture, said die being angularly displaceable on said supporting structure laterally relative to said punch.
5. In a device of the character described, in combination, a die having a vertically disposed aperture therein, and a punch member adapted to be introduced under pressure against an object mounted upon said die and into said aperture, said die being pivoted, and manual means for laterally

displacing said die on its pivot relative to said punch.

6. In a device of the character described, in combination, a supporting structure, a die carried thereby having a vertically disposed aperture therein, and a punch member of less diameter than said aperture carried by said supporting structure and adapted to be introduced under pressure against an object mounted upon said die and into said aperture, said die being angularly displaceable on said supporting structure laterally relative to said punch.

In witness whereof, I have hereunto subscribed my name this 25th day of March, A. D. 1927.

HUGO REICHEL
